CORNER BLOCK FOR MOLD STRIPS

Leonard C. Neufeld, Des Moines, Iowa

Application November 23, 1953, Serial No. 27,721

Term of patent 14 years

(Cl. D54—2)

FIG. 1

FIG. 2

FIG. 4

Fig. 1 is a perspective view of a corner block for mold strips showing my new design;

Fig. 2 is a top plan view;

Fig. 3 is a bottom plan view; and

Fig. 4 is a side elevational view.

I claim:

The ornamental design for a corner block for mold strips, substantially as shown.
